(57) **CLAIM**

The ornamental design for a combined sight impaired doll with musical instrument, clothing and dog, as shown and described.

DESCRIPTION

FIG. 1 is a front view of a combined sight impaired doll with musical instrument, clothing and dog embodying the design of the present invention.

FIG. 2 is a rear view thereof.

FIG. 3 is a side view as seen from the right of FIG. 1.

FIG. 4 is a side view as seen from the left of FIG. 1.

FIG. 5 is a top plan view thereof.

FIG. 6 is a bottom plan view thereof.

FIG. 7 is a perspective view thereof; and,

FIG. 8 is a front view of the doll shown without the musical instrument, eyeglasses, clothing, dog and hair.

The doll is shown alone in FIG. 8 to more completely disclose the doll, one characteristic feature of which resides in the indicia on the doll.
